UNITED STATES PATENT OFFICE.

CLIFFORD E. HAWKES, OF BROOKLYN, NEW YORK.

LAYOUT DEVICE.

1,370,645.

Specification of Letters Patent.

Patented Mar. 8, 1921.

Application filed September 9, 1919. Serial No. 322,632.

To all whom it may concern:

Be it known that I, CLIFFORD E. HAWKES, a citizen of the United States and resident of 183 Midwood St., Brooklyn, in the county 5 of Kings and State of New York, have invented certain new and useful Improvements in Layout Devices, of which the following is a specification.

This invention relates to layout devices, 10 that is, a tool for laying out work on a plane surface and has for an object to increase the accuracy of work of this character, facilitate the operation and increase the speed in laying out work of this character. 15 These objects are obtained by the construction shown in the accompanying drawings in which, Figure 1, is a plan view of my improved layout device, Fig. 2 is a side elevation, Fig. 3 is an end elevation, Fig. 4 is a 20 detail partly in section and Fig. 5 is a detail of an extension for the stand of the instrument.

In laying out work to be machined lines are transferred from the drawing to the 25 work and at the intersection of these lines center punch marks are made by hand to spot the drilling of holes, to mark the limits of a machining operation etc. The present invention provides for spotting these positions on the work by a micrometer adjustment directly from the lines of the drawing and provides a means whereby the center punch will spot the position with absolute 30 accuracy. This is an important feature of the invention as it is impossible, by hand, to position a center punch absolutely perpendicular to the surface on which it is used. It is also superior to center punches 35 with a guide inasmuch as it is located with a micrometer adjustment with absolute accuracy and without regard to irregularities 40 on the surface on which it is used.

This layout device consists of a surface plate 11 to which the four posts 12 are set 45 cured. On one side these posts support the slide bar 13 and on the other side they support the slotted bar 14. Across these two bars the slotted bar 15 is placed snugly fitting a groove in the saddle 16 which is maintained at right angles to bar 14 by a T nut 50 similar to 18, Fig. 4 engaging the slot 19 in this bar. Bar 15 supports the slide 17 which carries the main part of the mechanism. A lead screw 19 is provided in the 55 slot of bar 14 which is operated by handle 20, an index 23 being provided to show the

extent in decimal fractions of its operation. This screw engages the T nut on the under side of the saddle 16 and thereby moves cross bar 15 back and forth in response to handle 20. A similar lead screw 60 21 is provided in slot of bar 15 operated by handle 22 with a micrometer index 24 to show fractional movements. On the slide 17 a nut 18 is provided engaging with lead 65 screw 21, hence this slide is operated back and forth in response to handle 22. This construction is equivalent to a compound slide rest well known in certain classes of machine tools.

The center punch 31 is mounted in a sleeve 34 and held in the raised position by the spring 32, pins 33 being provided to limit its movement in the sleeve. This sleeve is accurately fitted into the extension 35 which is hinged at 36 to the slide 17 and therefore moves with this slide. The article which is to be marked is placed on the face plate 11, and the sides of the article may be positioned against the guide bars 51 and 52 on 80 the face plate; the center punch 31 is replaced by a set plug similar to 55 and positioned relative to the base line from which the dimension is to be read. Set plugs of this kind are well known in the tool-making 85 art, consisting as shown in Fig. 4, of a conical point with a flat side, this flat side can be accurately sighted on the base line from which the dimensions are read. The lead screw 20 is now operated until the graduated scale 25 and the index 23 measure off the dimension required, this locates the position in one direction. This operation is repeated with reference to moving slide 17 from another base line according to the dimensions indicated by the scale 26 and the index 24, this locates an intersecting position upon imaginary lines drawn from two sides and thus accurately locates the position for the center punch without scribing 90 95 the work and without disturbing the setting of the center punch after it is obtained.

The set plug is replaced by the center punch in sleeve 34 and a tap from the hammer locates the point.

The extension 35 is positioned horizontally by the knuckle 61 on hinge 36, this part, however, is free to turn upward in the arc of a circle, the hinge member being cut away at 62 for this purpose the angle 110 through which it moves being indicated by the protractor 37 secured in place by the

hinge pin and remains rigid with slide 17, this enables the punch to be positioned at right angles to the base plate 11 and its angular position can be easily seen from the 5 graduations on protractor 37. An additional and important feature is that the entire mechanism carried by extension 35 can be turned up at a right angle to clear lugs that may be protruding from the work 10 inserted below. This movement also enables the work to be quickly and easily inspected and forms a yielding connection in case the punch 31 is accidentally obstructed.

This gage also provides for measuring 15 angles about a center located by punch 31. This is secured by the horizontal protractor 45 which carries the plate 48 Fig. 4, and is arranged to move about the axis of punch 31. The zero mark of the protractor corresponds to a zero mark on 35 (not shown) 20 when in the position shown in Fig. 1. Angular variations in either direction can thus be easily read. An adjustable extension 42 is secured to this plate by the screw 44 engaging the slot 43 in extension 42. A sleeve 41 similar to sleeve 34 is inserted in the end 25 of 42, in which sleeve a punch similar to 31 may be inserted. This punch can, therefore be used to accurately set off angles as indicated by the protractor 45 at various 30 radii about a center which is located by the micrometer adjustment. The supporting posts 12 may be unscrewed in the middle and extensions 12^a, Fig. 5, inserted to 35 lengthen these posts when it is desired to increase the height of the punches above the base plate.

Having thus described my invention, I 40 claim:

1. In a layout device of the class described, a base plate, supporting a stand, a movable carriage on said stand supporting a spring retrieved center punch, means whereby said punch may be moved at an 45 angle to said base plate and means for adjusting the position of said carriage in two directions.

2. In a layout device of the class described, a base plate supporting a stand, a

carriage, a plurality of micrometer screws, 50 said screws arranged to move said carriage on said supporting stand, a spring retrieved punch supported by said carriage, means for operating said micrometer screws for positioning said carriage in two directions 55 and means whereby said center punch may be moved angularly in a vertical plane.

3. In a layout device of the class described, a base plate supporting a stand, a movable carriage on said stand supporting a center punch, micrometer means for positioning said carriage in two directions at right angles to each other, means whereby said punch may be moved angularly in a vertical plane, and an index to show the position of said punch.

4. In a layout device of the class described, a base plate supporting a stand, a movable carriage supported by said stand and supporting a center punch, a set plug, 70 a horizontal protractor having the same axis as said center punch, an adjustable extension arm secured to said protractor and adapted to support said set plug.

5. In a layout device of the class described, 75 a base plate supporting a stand, a movable carriage supported by said stand and supporting a center punch, a set plug, a protractor having the same axis as said center punch, an arm secured to said protractor 80 and adapted to support said set plug, micrometer means for positioning said carriage in two directions and means whereby said set plug may be positioned by said protractor.

6. In a layout device of the class described, a base plate supporting a stand, a movable carriage supported by said stand and supporting a center punch, a protractor having the same axis as said center punch 90 and supporting a set plug, said carriage being movable in a horizontal plane, and means whereby said center punch and set plug may be moved in a vertical plane.

Signed at Brooklyn, in the county of 95 Kings and State of New York this 3rd day of Sept. A. D. 1919.

CLIFFORD E. HAWKES.
